P. Edwards

ATTORNEY

UNITED STATES PATENT OFFICE.

ALBERT L. LAMBERT, OF NARBERTH, PENNSYLVANIA, ASSIGNOR TO HEINTZ MANUFACTURING COMPANY, OF PHILADELPHIA, PENNSYLVANIA, A CORPORATION OF PENNSYLVANIA.

VEHICLE DOOR CONSTRUCTION.

Application filed September 15, 1923. Serial No. 662,803.

This invention relates to doors for automobile bodies, and more particularly relates to sheet metal doors.

The aim of my invention is to provide a sheet metal door for automobile bodies which is of simple, durable and inexpensive construction, having pleasing appearance and finish, and to provide a door which may be assembled at low cost. Other objects of my invention will be in part obvious and in part pointed out hereinafter.

The invention accordingly consists in the features of construction, combinations of elements and arrangement of parts which will be exemplified in the construction hereinafter set forth and the scope of the application of which will be indicated in the following claims.

In order that a clearer understanding of my invention may be had, attention is here directed to the accompanying drawings forming a part of this application and illustrating certain possible embodiments of my invention. Referring to the drawings, Fig. 1 is a rear plan view of a door embodying my invention, a portion of the upholstery pad being broken away; Fig. 2 is a vertical sectional view of the door and is taken on the line 2—2 of Fig. 1; Fig. 3 is a horizontal sectional view of the door and is taken on the line 3—3 of Fig. 1; Fig. 4 is a horizontal sectional view of a flush type door embodying my invention; and Fig. 5 is a vertical sectional view of the lower portion of the door and is taken on the line 5—5 of Fig. 4. Similar reference characters refer to similar parts throughout the several views of the drawings.

Referring to the drawings, the body of the door of the overlapping type, as shown in Figs. 1, 2 and 3, comprises a sheet metal pan portion 1 and a sheet metal cover or outer panel 2. The pan portion 1 has a major portion forming the rear of the door body and a forwardly extending bottom flange 3 which ends in a downwardly extending flange 4 adapted to be received and tightly secured in the fold or doubled-over portion 5 provided along the lower edge of the outer panel 2. The pan portion 1 at each side is provided with forwardly extending flanges 6 and 7 having outwardly turned edges 6' and 7' respectively seated

and securely held in the folded or double-over portions 8 and 9 formed along the side edges of the outer panel 2. The flange 6 at the opening side of the door is preferably stepped or otherwise suitably contoured according to the shape of the adjacent door jamb portion 10 of the vehicle body 11. At the hinge side the flange 7 may be straight. An angle iron reenforcing strip 12 is preferably located on the interior of pan portion 1 so as to abut the flange 7 and the adjacent portion of the rear of the pan so as to reenforce the construction. This side of the door has secured thereto, as by means of screws 13, a hinge 14 of conventional type which is also secured to the adjacent jamb portion 15 of the vehicle body 11. The portions 5, 8 and 9 in a door of this type are preferably arranged to overlap the body 11 at the bottom and sides of the door opening. At the top of the door the portion 1 ends in a rearwardly overhanging flange 16 and the top of panel 2 is extended rearwardly over the top of the door and ends in a similar overhanging flange 17 which fits over the flange 16. These flanges preferably are secured together by welding. The depression 18 created by providing these overhanging flanges provides room for the insertion of an electric welding tool to effect the welding operation without its showing on the visible surface of the flange 17. Along the lower edge of portion 1 there is welded a strip 19 which has an upwardly opening groove 20 along its lower edge. This construction permits a pad 21 of cardboard or buckram to have its lower edge seated in the groove 20 and its upper groove seated in the recess 18 whereby the pad is held in place on the door. The pad of such material is sufficiently flexible, so that by bending the pad into the shape shown on dot and dash lines in Fig. 2, as at 21', its upper and lower edges may be snapped into the retaining grooves 18 and 20. Preferably the portion 1 is provided with suitable offset portions, such as 23 and 24, which locate and reenforce the pad 21. The portion 1 is also preferably formed with a sunken panel portion, such as 25, or a cutout portion 26, providing a pocket in the door. The pad 21 may have a similar cutout portion 27 which, if present, is pref-

erably covered by a liftable cover 28 which is suitably secured along its top 29 to the pad 21.

Referring to Figs. 4 and 5, it will be seen that a door of the flush type may be constructed in a manner substantially similar to the construction of a door of the overlapping type. In this type of door, however, instead of extending the bottom and side edges of the pan portion and outer panel of the door so as to overlap the bottom and sides of the door opening, these flanges are omitted. For instance, the bottom flange 30 of the pan portions 1' ends within the doorway and the outer panel 2' has an inwardly extending bottom flange 31 which overlaps flange 30 and is preferably secured thereto by welding or the like. Similarly, the side flange 32 of pan 1' at the opening side is overlapped by inwardly extending flange 33 provided on the adjacent edge of outer panel 2', and these flanges are preferably secured together, as by welding. At the hinge side of the door the edge of pan portion 1' has a folded or doubled-over portion 34 ending in a forwardly extending bead 35, and the corresponding edge of the outer panel 2' has a folded or doubled-over portion 36 ending in a rearwardly extending bead 37. A U-shaped reenforcing strip 38 forms a part of the door along this edge. The wall 39 of strip 38 is exposed along the side of the door, and one wall 40 of this strip abuts behind and is secured, as by welding, to the doubled-over portion 36 of the outer panel 2', while the other wall 41 of member 38 abuts and is secured, as by welding, to the double portion 34 of pan portion 1'. This construction permits of the welding of channel member 38 to the outer panel 2' without showing welding marks on the outside of panel 2', since the welding operation need not be extended more than will be sufficient to join the wall 40 to the inner fold of double portion 36. The channel member 38 preferably is suitably recessed, as at 42, to receive the beads 35 and 37. The hinge 14 may be secured to the door by means of screws 13 which engage in suitable threaded perforations in the doubled portion 34 and the wall 41 of channel member 38. With this type of door the bottom of the doorway 11 is preferably stepped, as at 43, and the bottom wall 30 of the door is of correspondingly stepped formation. The remainder of the construction is similar to that described and shown in connection with the overlapping type of door.

In either type of door the pad 21 of upholstery in addition to being secured to the door by means of retaining grooves 18 and 20, may be further secured by means of nails 44 which engage the pad 21, and which also are tightly held within slots 45 provided

at suitable points in the pan portion 1 or 1' of the door. Nails are used which are larger in diameter than the width of the slots 45, so that when a nail is driven into a slot, the edges of the slot will be flexed and will be pinched against the nail, and whereby the nail will be securely held in the slot. This method of nailing is described and claimed in an application filed by me on even date herewith, Serial No. 662,802. 75

Among the advantages obtained from the above construction of door is that the overhanging flanges 16 and 17 prevent rain from going behind the upholstery. These flanges also shield the upholstery from wear from a person's hand or otherwise. The construction eliminates the necessity of using nails across the top or bottom of the door. By inserting the upholstery pad in the manner described, it may be inserted and held in place without chafing. The construction, moreover, is such that all welding may be accomplished from the underneath or inside portions of the construction, and in such a way that none of the welding need show on any part of the door which is normally exposed to view.

As many changes could be made in the above construction and as many apparently widely different embodiments of this invention could be made without departing from the scope thereof, it is intended that all matter contained in the above description or shown in the accompanying drawings shall be interpreted as illustrative and not in a limiting sense.

What I claim is:

1. In a door of the character described, in combination, a rear panel having along its upper edge an overhanging flange spaced rearwardly of the panel, a front panel member having a portion extending rearwardly over the top of the door and having an overhanging flange fitting over the overhanging flange of said rear panel, an upholstery pad on the rear of the door, the upper edge of said pad being seated behind and overlapped by said overhanging flanges, and an offset formed on the rear panel seating against said pad and locating the top edge of the pad closely against said overhanging flanges.

2. In a door of the character described, in combination, a rear panel portion having forwardly extending flanges along its bottom and each side and a rearwardly overhanging flange along its top edge, and a front panel portion having flanges along its bottom and each side connected with the said bottom and side flanges of said panel portion and having along its top a flange extending rearwardly over the top of the door and overlapping and secured to the overhanging flange at the top of said panel portion.

3. In a door of the character described, in combination, a rear panel portion having forwardly extending flanges along its bottom and each side and a rearwardly overhanging flange along its top edge, a front panel portion having flanges along its bottom and each side connected with the said bottom and side flanges of said panel portion and having along its top a flange extending rearwardly over the top of the door and overlapping and secured to the overhanging flange at the top of said panel portion, an upwardly open channel along the lower edge of the door, and an upholstery pad having its bottom edge seated in said channel and its top edge seated behind said overhanging flange, said panel having an offset portion adjacent said overhanging flange, 35 whereby the upholstery pad is held tightly against said flange. 30
4. In a door of the character described, in combination, a rear panel portion having forwardly extending flanges along its bottom and each side and a rearwardly overhanging flange along its top edge, a front panel portion having flanges along its bottom and each side connected with the said bottom and side flanges of said panel portion and having along its top a flange extending rearwardly over the top of the door and overlapping and secured to the overhanging flange at the top of said panel portion, said panel having narrow slots enlarged at the ends, whereby the sides of said slots are rendered resilient, an upholstery pad positioned against said panel, and nails engaging said pad and penetrating said slots and securing the pad to the panel. 50 45 55
- This specification signed this 11th day of September, 1923.

ALBERT L. LAMBERT.
